BOOT AND SHOE CLEANER

Harry C. Gilpin, Huntington, W. Va.

Application February 7, 1939, Serial No. 255,114

3 Claims. (Cl. 15—161)

This invention relates to a boot and shoe cleaning device and it is one object of the invention to provide a device of this character which may be set in place in a vestibule or similar location and mud and dirt easily and very thoroughly removed from shoes.

Another object of the invention is to provide a device of this character including a base plate which is firmly but removably held in place and serves as a receptacle for catching mud and dirt and also serves as a tray in which the accumulated mud and dirt may be conveyed to a place of disposal.

Another object of the invention is to provide a shoe cleaner wherein brushes for cleaning side portions of a shoe are mounted at opposite sides of a brush for cleaning the bottom of the shoe, the side brushes being yieldably held against movement away from the bottom brush and urged into cleaning engagement with side portions of the shoe.

Another object of the invention is to provide the cleaner with a blade or plate for scraping mud from the bottom of a shoe, the said scraping blade having its upper edge level with bristles of the bottom brush and lugs or ears being provided at opposite ends of the upper edge of the plate for guiding movement of the shoe across the plate and also for scraping mud from side edges of the shoe sole.

Another object of the invention is to provide a bottom brush having slots formed therein whereby dirt scraped from a shoe may pass through the block or back of the brush and into the pan or base plate where it will be held until dumped from the pan.

Another object of the invention is to provide an improved shield for the spring which urges the side brushes toward the center brush and also shields for the hinges by means of which the side brushes are pivotally mounted. It will thus be seen that the mud and dirt will be prevented from clogging the spring and the hinges and preventing proper movement of the side brushes.

Another object of the invention is to provide a shoe cleaner which is simple in construction, strong and durable, and not liable to be easily broken or get out of working order.

The invention is illustrated in the accompanying drawings wherein:

Figure 1 is a top plan view of the shoe cleaner.

Fig. 2 is a sectional view taken longitudinally through the shoe cleaner along the line 2—2 of Fig. 1.

Fig. 3 is a longitudinal sectional view taken along the line 3—3 of Fig. 1.

Fig. 4 is a transverse sectional view taken along the line 4—4 of Fig. 1.

Fig. 5 is a transverse sectional view taken along the line 5—5 of Fig. 1.

Fig. 6 is a sectional view taken along the line 6—6 of Fig. 1.

Fig. 7 is a fragmentary sectional view showing a side brush shifted away from the bottom brush.

Fig. 8 is a fragmentary sectional view showing the scraper mounted upon the base plate instead of upon the back of the bottom brush.

The base 1 of this shoe cleaner is formed from a plate of sheet metal having its marginal portions bent upwardly to form an upstanding rim or wall 2 serving to retain mud and dirt upon the base plate and thus permit the base plate to constitute a tray for carrying the mud and dirt to a place of disposal. Strips 3 are secured across the under face of the ends of the base plate by screws 4 which may also serve as securing elements for vacuum cups 5. These cups have gripping engagement with the surface upon which they rest and firmly hold the shoe cleaner in place but permit the shoe cleaner to be lifted and accumulated mud and dirt dumped from the base plate or tray when so desired. If so desired, the vacuum cups may be eliminated and screws used which are of sufficient length to pass through the strips 3 and engage in the floor or other surface upon which the shoe cleaner rests.

Over the base plate 1 are mounted a bottom brush 6 and side brushes 7 and a scraper 8 which is formed from a plate of stiff sheet metal and has its lower end portion bent to provide an attaching flange 9. The flange may be secured against the under face of one end of the back or block 10 of the bottom brush by screws 11 or it may be secured to the base plate by bolts 12 as shown in Figure 8. In either case, the scraper will be mounted in a vertical position across the front end of the bottom brush with its upper edge flush with upper ends of the tufts of bristles 13 as shown in Figure 2. The tufts of bristles 13 are arranged in rows extending transversely across and longitudinally of the back or block 10 and between the longitudinally extending rows of bristles, the back is formed with slots 14 constituting passages for dirt removed from shoes by the bristles of the brush. Therefore, the dirt will not accumulate in the brush between the bristles and clog the brush. This dirt, and also mud and dirt scraped from shoes by the scraper 8, will accumulate in the pan or base 1 and when a

certain quantity has gathered in the pan, the pan will be loosened from the surface upon which it rests and the shoe cleaner carried to a place of disposal where the dirt will be dumped from the pan. The shoe cleaner will then be restored to its original position for use.

Referring to Figure 2, it will be seen that the tufts of bristles 13 gradually increase in height from ends of the bottom brush toward its mid-length. Therefore, when a shoe is applied to the scraper and drawn rearwardly across the same, it will move onto the bottom brush with a good rubbing action taking place between the bristles of the brush and the bottom of the shoe and any mud or dirt which is not scraped from the heel and sole of the shoe by the scraper will be removed by the bottom brush. Ears 15 extend outwardly and upwardly from upper corners of the scraper and constitute guides for retaining a shoe in its proper position across the upper edge of the scraper and also serve as cleaning members for scraping mud and dirt from side edges of the sole and heel of a shoe.

In order to mount the bottom brush over the base or pan, there have been provided cross bars or bolsters 16 which rest upon metal strips 17. Screws 18 pass upwardly through the base and the strips 17 and bolsters 16 into the back of the bottom brush as shown in Figure 4 to firmly secure the brush in place and there have also been provided bolts 19 which in addition to securing the cross bars and the strips 17 to the base also serve as means for securing shields 20 upon upper faces of end portions of the cross bars which project from opposite sides of the bottom brush. The cross bars or bolsters not only serve as mounting means for the bottom brush but also serve as spacers for supporting the bottom brush in an elevated position and providing space below this brush so that the dirt can drop through the slots 14 onto the base or pan and flow from under the brush when emptying dirt from the pan.

End portions of the strip 17 which may be referred to as a hinge strip or leaf project beyond ends of the bolsters 16 and are formed with hinge ears 21 with which companion hinge ears 22 at lower ends of hinge strips or leaves 23 are pivotally connected by hinge pins 24. The hinge leaves or strips 23 are secured against outer faces of the backs 25 of the side brushes 7 by screws 26 and thus mount the side brushes for swinging movement from the normally upright position shown in Figures 4 and 5 toward a deflected position away from the bottom brush as shown in Figure 7. The side brushes are to be yieldably held in the upright position and urged back toward this position for cleaning engagement with side portions of a shoe.

In order to do so, there has been provided a helical spring 27. This spring is housed in a metal tube 28 serving as a shield for the same and the spring and its shield extend transversely under the back of the bottom brush midway the length thereof. The upper portion of the tube engages in a groove 29 formed in the under face of the back of the bottom brush and its lower portion rests in the channel of a saddle plate 30 which is secured to the brush back by screws 31. This tubular shield serves very effectively to retain the spring in its proper position and also as means for preventing dirt from gathering between convolutions of the spring and clogging it. Therefore, the spring may always contract freely and exert pull upon the side brushes to yieldably hold them in an upright position and maintain their

bristles in rubbing engagement with side portions of a shoe when the side brushes are forced outwardly toward a lowered position by a shoe disposed between them upon the bottom brush and the scraper for cleaning of the shoe.

The shields 20 serve to prevent mud and dirt from gathering upon the hinges for the lower ends of the hinge leaves and preventing easy swinging movement of the side brushes. By having end portions 32 of the tube 28 bent upwardly as shown in Figure 5, end portions of the spring will be deflected upwardly toward the side brushes to which its ends are secured by the screws 33 and pull upon the side brushes be exerted in such a manner that the side brushes will be held in good rubbing engagement with side portions of a shoe.

It will thus be seen from the foregoing description that I have provided a boot and shoe cleaner that will at all times be positive and efficient in carrying out the purposes for which it has been designed and due to its simplicity, it can be readily and easily disassembled whenever any of the parts need replacing. Further, a device of the present character can be manufactured and sold at a very reasonable cost.

While I have shown the preferred embodiment of my invention, it is to be understood that various changes in size, shape and arrangement of parts may be resorted to without departing from the spirit of the invention and the scope of the appended claims.

Having thus described the invention, what is claimed is:

1. A shoe cleaner comprising a base, a bottom brush mounted horizontally over said base in an elevated position, side brushes normally disposed vertically at opposite sides of said bottom brush and hinged along their lower edges to the bottom brush for swinging movement towards and away from the bottom brush, a tube mounted against the under face of the back of said bottom brush transversely thereof with its end portions projecting from sides of the bottom brush and deflected upwardly to extend diagonally towards the side brushes, and a helical spring passing through said tube with its end portions projecting from ends of the tube and secured to lower edge portions of backs of the side brushes, said spring yieldably resisting swinging movement of the side brushes away from the bottom brush and urging the side brushes inwardly into position for rubbing engagement with a shoe disposed between the side brushes and resting upon the bottom brush.

2. A shoe cleaner comprising a base, a bottom brush mounted horizontally over said base in an elevated position, side brushes disposed vertically at opposite sides of said bottom brush and extending longitudinally thereof, hinge members carried by said brushes and mounting the side brushes for swinging movement toward and away from the bottom brush, a tube extending under the back of the bottom brush transversely thereof and engaged in a groove formed in the back intermediate its length, a saddle plate secured against the under face of the back of the bottom brush and formed with a channel receiving said tube, said tube having its end portions projecting from sides of the bottom brush and deflected upwardly, and a spring extending through said tube with its end portions projecting outwardly therefrom and secured to lower portions of said side brushes and exerting inward pull urging the side brushes towards the bottom brush.

3. A shoe cleaner comprising a base, a bottom brush over said base, bolsters extending under said bottom brush transversely thereof for supporting the bottom brush in an elevated position relative to the base, hinge strips under said bolsters having their end portions projecting from ends of the bolsters and formed with hinge ears, side brushes, hinge strips carried by said side brushes with end portions projecting downwardly 5 therefrom and formed with hinge ears pivoted to

the hinge ears of the first hinge strips to mount the side brushes for vertical swinging movement toward and away from the bottom brush, shields for the hinge ears carried by the projecting end portions of said bolsters, and a spring extending under the bottom brush with its ends secured to said side brushes and yieldably resisting swinging movement of the side brushes away from the bottom brush. 5

HARRY C. GILPIN. 10
